E. A. SNOW

SOCKET FOR ELECTRIC LAMPS

Filed Dec. 27, 1921.

FIG. 1.

FIG. 4.

FIG. 3.

Inventor:

Eugene A. Snow.

By Frank D. Thomason.

Attorney.

UNITED STATES PATENT OFFICE.

EUGENE A. SNOW, OF RIVER FOREST, ILLINOIS.

SOCKET FOR ELECTRIC LAMPS.

Application filed December 27, 1921. Serial No. 524,851.

To all whom it may concern:

Be it known that I, EUGENE A. SNOW, a citizen of the United States, residing at River Forest, in the county of Cook and 5 State of Illinois, have invented certain new and useful Improvements in Sockets for Electric Lamps, of which the following is a full, clear, and exact description.

My invention relates to sockets of electric lamps particularly of the kind for 10 which Letters Patent of the United States were granted to me November 8, 1921, Number 1,396,294, and to electric lamps which heretofore have been in some cases so constructed that when it was desired to focus 15 incandescent electric lamps used in reflectors, particularly of automobiles, it was necessary to loosen a set-screw and adjust the lamp in the desired position, and then 20 tighten the screw again. This, considering the position of the reflector, took both time and labor.

The object of my invention is to provide 25 a simple and comparatively inexpensive improvement to the socket of the lamp, whereby such an adjustment of the lamp can be accomplished easily and quickly by hand through the medium of a projecting handle, substantially as hereinafter fully explained 30 and as particularly pointed out in the claims.

In the drawings:

Figure 1 is a longitudinal central section 35 of a lamp socket embodying my improvements and the reflector attached thereto and a side view of a lamp adjustably inserted therein.

Figure 2 is a transverse section of the 40 same taken on dotted line 2, 2, Figure 1, looking in the direction indicated by the arrows.

Figure 3 is a side view of the upper broken away portion of the reflector socket holder and lamp socket, shown in Figure 1.

Figure 4 is a detail view showing a central section of the socket holder.

In the drawings A represents an electric incandescent lamp constructed in the usual manner and provided with what is known to 50 the trade as an Edison base, B, that is, a cylindrical base or plug having one, or, usually two diametrically opposite short pins b, b, projecting therefrom. When in use the base of the lamp is inserted in its 55 cylindrical metallic socket C, and these pins enter bayonet slots c and move longitudi-

nally therein to the ends of said slots, and the lamp is then turned on its axis to cause the pins to enter the lateral portions of the slots, in which they are retained by the 60 pressure of a yielding electrode.

My improvements employ the same lamps and sockets now in extensive use, but the tubular boss or holder D in which said socket C is secured is constructed differently. 65 This metallic boss D, has the annular edge of the central opening of a reflector E seated and secured in a circumferential groove, or annular rabbet e, made next the outer end of said boss, substantially as shown in the drawings, but the reflector may be secured thereto in any other manner, or the boss may be used in conjunction with any other 70 form of a reflector.

The diameter of the entrance of the bore 75 of the boss, at its front end, is but slightly greater than the circumference of the socket C, but to the rear of said front entrance the bore is increased in diameter and forms a seat f for a coil-spring, F. The rear convolution 80 of this spring is seated in an annular groove g made in said bore, and the rear end thereof is bent outwards and enters and is secured in a suitable perforation G in the wall 85 of the boss. The front end of the spring is unsecured and the normal diameter of the bore of the spring is slightly less, say, one thousandth of an inch than the outer circumference of the socket. This spring F is turned radially or transversely outwards 90 and passes through a segmental slot h in the holder D and on the outside of the same has a handle H, securely fastened thereon, which latter can be engaged by the fingers and pushed to the right whenever it is desired to 95 loosen the coils of the spring.

In operation the socket can be easily inserted in boss D by properly manipulating the handle H to expand the spring. It can be locked by releasing the hold on the handle, and can thereby be retained in any position to which it may be adjusted.

It will be obvious to others that modifications and other adaptations of my invention may be made without departing from the 105 principles or scope of the claims, and I therefore desire it understood that all such changes or uses are fully contemplated within said claims.

What I claim as new is:

1. The combination of an electric lamp socket, a holder therefor, said holder com-

- prising a hollow cylinder having a peripheral circumferential elongated slot, a helical spring disposed within said holder and surrounding said socket, one end of said spring being anchored to said holder, the other end of said spring being free, and a lug integral with said free end projecting through said slot, the tension of the spring being such that the lug tends to move towards one end 5 of the slot, whereby the spring grips the said socket, and manual movement of the lug towards the other end of said slot tends to unwind the spring and thereby permit free movement of the socket.
- 10 2. In a focusing device for electric lamps, a tubular boss having adjacent to one end an external recess, a reflector which is fixedly attached to the boss a part thereof being seated in said recess, an internal shoulder located adjacent to the end of the boss 15
- 20

having the external recess, the boss having a circumferential elongated slot adjacent the internal shoulder and an internal recess adjacent the opposite end of the boss, a helical spring maintained within the boss by engagement at one end with the internal recess, a tubular lamp socket that is maintained in place by frictional engagement with the inner surfaces of the helical spring, and a lug integral with the other end of 25 said spring and passing through the slot, whereby the spring may be unwound so as to permit free movement of the said socket.

In witness whereof I hereunto set my hand this 13th day of December, 1921.

EUGENE A. SNOW.

Witnesses:
